VENTILATION SYSTEM FOR MINES

Jack R. Kennedy and Samuel F. Kennedy, Taylorville, Ill.

Application August 21, 1953, Serial No. 375,615

10 Claims. (Cl. 61—45)

This invention relates to a prefabricated, telescoping, and easily installed ventilation arrangement or overcast structure for use in mines, and utilizes the type of structures as disclosed in the co-pending application Serial Number 350,557, filed April 23, 1953, for Mine Stopping.

An object of this invention resides in the provision of means for preventing the intermingling of the air and gas in a coal shaft with that of an intersecting shaft to thereby reduce the expense necessary in ventilating a mine by eliminating the necessity for providing fresh air to the unused portions while maintaining continuity of air passage ways in the intersecting shafts.

The construction of this invention features the use of a recess formed in the top of a cross shaft of a mine at the point where it intersects with another shaft. Supported within the recess is a substantially rectangular conduit. The other portions of the cross shaft are blocked by suitable mine stopping.

Another object of the invention resides in the provision of a novel construction for a ventilation conduit or overcast structure for use in mines which employs telescoping panels thereby permitting the panels to form conduits of various lengths as may be necessary. Further, the conduits can be substantially prefabricated at a point remote from the site of installation, the arrangement of parts being flexible enough to compensate for various irregularities existing in the shape and size of the intersecting shafts.

The mine stopping employed in conjunction with the ventilating conduit is of a salvagable nature as is the conduit thereby enabling the use and reuse of the parts thereof as mining operations progress which results in a considerable saving and reduced expense of operation of the mine.

Still further objects and features of the invention reside in the provision of a ventilation system for mines that is simple to install by even semi-skilled labor, constructed from a minimum number of interchangeable parts, which is easily caulked for complete prevention of flow of air through any of the walls formed by the parts thereof, yet which may be easily disassembled and salvaged for reuse.

These, together with the various ancillary objects and features of the invention which will become apparent as the following description proceeds, are attained by this ventilation system for mines, a preferred embodiment of which has been illustrated in the accompanying drawings by way of example only, wherein:

Figure 1 is a plan view illustrating the manner in which the ventilation system is utilized in a mine;

Figure 2 is an elevational view illustrating the manner in which the top of the mine is recessed for reception of the conduit, the direction of the view being taken along the plane of line 2—2 in Figure 1;

Figure 3 is a vertical sectional view as taken along the plane of line 3—3 in Figure 1 and illustrating the arrangement of the mine stopping and rectangular ventilation conduit used in the invention;

Figure 4 is an enlargement of portions of Fig. 3 affording a sectional detail view of the rectangular conduit

2

constructed from the various elements utilized in this invention;

Figure 5 is a sectional detail view as taken along the plane of line 5—5 in Figure 4;

Figure 6 is an enlarged sectional detail view showing the manner in which the rectangular frame for the conduits is assembled; and

Figure 7 is a perspective view of one of the substantially U-shaped clamps utilized in this invention.

10 With continuing reference to the accompanying drawings wherein like reference numerals designate similar parts throughout the various views, reference numeral 10 generally designates a shaft in a mine having cross shafts 12, 14, and 16 intersecting therewith. The construction of this invention provides means for permitting ready passage along the shaft 10 permitting continuity of flow of air between the cross sections 18 and 20 of the shaft 14.

15 In order to achieve the desired results, the top or overhead 22 of the cross shaft 14 is recessed as at 24. The recess 24 is of sufficient size to receive a rectangular conduit 26 therein and the end portions of the recess 24 and 26 are tapered downwardly until they reach the level of the top of the shaft 20.

20 The rectangular conduit 26 is supported by suitable standards 28 on which I-beams 30 or other suitable supporting elements are mounted. Extending upwardly from the bottom 32 of the cross shaft 14 and closing the sections 18 and 20 thereof are mine stoppings 34 and 36 of the character described in the co-pending application, Serial Number 350,557 for Mine Stopping.

25 Each of the mine stoppings 34 and 36 includes pairs of vertically telescoping panels 38 and 40 which are clamping held together in abutting relationship to brace bars 42 in a manner such as to permit the pairs of panels 38 and 40 to telescope should there be an upheaval of the bottom of the mine resulting from a squeeze. The panels 38 and 40 are substantially channel shaped and are clamping held to the support bars 42 by means of U-shaped clamp members such as those indicated in Figure 7 and indicated by reference numeral 44 having U-shaped clamping plates 46 and threaded rods 48 attached thereto. Clamping elements are received over the threaded end of the rods 48, and are indicated at 49.

30 The rectangular conduit 26 is composed from suitable rectangular frames 50 including top and bottom frame members 52 and 54 together with side frame members 56 and 58. The frames 50 are formed from or angle shaped in cross section and are bolted together as indicated at 59 in Figure 6.

35 Supported on the frames 50 there are telescoping pairs of outer and inner panels 60 and 62 which are arranged in abutting relationship and alternately the inner panel terminates at one side and at the other. This is because this arrangement permits the panels 60 and 62 to intermesh to the greatest extent thereby decreasing the air space between those panels; thus reducing the amount of caulking necessary to completely prevent any flow of air through the interstices between the panels. Each of the panels 60 and 62 are substantially channel shaped and have converging L-shaped flanges 64, 66, and 68, 70 respectively.

40 In order to hold the panels 60 and 62 against the frames 50 there are provided clamping means comprising the substantially U-shaped plates 46 having the threaded rods 48 press fitted therein. The rods 48 extend through the frames 50 and the U-shaped plates 46 engage the L-shaped flanges 64, 66, and 68, 70 in such manner as to resiliently hold the panels 60 and 62 in engagement with the frames 50. The rods 48 have

45 threadedly secured thereon suitable nuts 49 which engage the frames 50. The precise amount of tension on the rods 48 should be such as to permit ready telescoping

of the inner panels 62 within the outer panels 60 in order that the conduit 50 may be readily adjusted so as to be properly fitted in the recess 24. The precise amount of telescoping relationship between the panels 60 and 62 is determined, of course, by the width of the shaft 10. It is to be noted that the panels 60 and 62 secured to the top frame members 52 will overlap the panels secured to the side frame members 56 and 58. In order to insure proper rigidity of the conduit 26 there is provided a brace 72 which is terminally secured to the side frame member 58 and to the bottom frame member 54. Since the brace 72 will prevent collapse of the side frame member 58 relative to the bottom frame member 54, it will maintain the entire frame 50 relatively rigidly in a rectangular shape. Obviously, a suitable number of braces 72 may be utilized noting that the braces 72 would provide some obstruction to the flow of air, and it is therefore intended that a minimum number of these braces be utilized.

Since from the foregoing the construction and advantages of this ventilation for mines are readily apparent, further description is believed to be unnecessary.

However, since numerous modifications will readily occur to those skilled in the art, after consideration of the foregoing specification and accompanying drawings, it is not intended to limit the invention to the precise embodiments shown and described, but all suitable modifications and equivalents may be readily resorted to.

What is claimed as new is as follows:

1. A ventilation system for mines having a mine shaft including an overhead, said mine shaft being intersected by a cross shaft, said cross shaft having an overhead forming a recess in the overhead of said mine shaft, a substantially rectangular conduit received in said recess, and vertically extending stoppings in said cross shaft extending from the bottom of said cross shaft to said conduit and closing said cross shaft relative to said mine shaft at each side of said mine shaft.

2. A ventilation system for mines having a mine shaft including an overhead, said mine shaft being intersected by a cross shaft, said cross shaft having an overhead forming a recess in the overhead of said mine shaft, a substantially rectangular conduit received in said recess, and vertically extending stoppings in said cross shaft extending from the bottom of said cross shaft to said conduit and closing said cross shaft relative to said mine shaft at each side of said mine shaft, said conduit including pairs of horizontally telescoping panels, and means holding said pairs of panels in abutting relationship.

3. A ventilation system for mines having a mine shaft including an overhead, said mine shaft being intersected by a cross shaft, said cross shaft having an overhead forming a recess in the overhead of said mine shaft, a substantially rectangular conduit received in said recess, and vertically extending stoppings in said cross shaft extending from the bottom of said cross shaft to said conduit and closing said cross shaft relative to said mine shaft at each side of said mine shaft, said conduit having a plurality of rectangular frames, pairs of horizontally extending panels, and clamp members extending through said frames clamping said panels to said frames.

4. A ventilation system for mines having a mine shaft including an overhead, said mine shaft being intersected by a cross shaft, said cross shaft having an overhead forming a recess in the overhead of said mine shaft, a substantially rectangular conduit received in said recess, and vertically extending stoppings in said cross shaft extending from the bottom of said cross shaft to said conduit and closing said cross shaft relative to said mine shaft at each side of said mine shaft, said conduit having a plurality of rectangular frames, pairs of horizontally extending panels, and clamp members extending through

said frames clamping said panels to said frames, said pairs of panels being arranged to form a top, bottom, and side walls for said conduit, said frames having top, bottom, and side frame members, and brace means terminally secured to said bottom frame member and a side frame member to rigidify said conduit.

5. A ventilation system for mines having a mine shaft including an overhead, said mine shaft being intersected by a cross shaft, said cross shaft having an overhead forming a recess in the overhead of said mine shaft, a substantially rectangular conduit received in said recess, and vertically extending stoppings in said cross shaft extending from the bottom of said cross shaft to said conduit and closing said cross shaft relative to said mine shaft at each side of said mine shaft, said conduit including pairs of horizontally telescoping panels, and means holding said pairs of panels in abutting relationship, each of said panels being substantially channel shaped, said means comprising clamps having substantially U-shaped plates engaging said channel-shaped panels.

6. A ventilation system for mines having a mine shaft including an overhead, said mine shaft being intersected by a cross shaft, said cross shaft having an overhead forming a recess in the overhead of said mine shaft, a substantially rectangular conduit received in said recess, and vertically extending stoppings in said cross shaft extending from the bottom of said cross shaft to said conduit and closing said cross shaft relative to said mine shaft at each side of said mine shaft, said conduit having a plurality of rectangular frames, pairs of horizontally extending panels, and clamp members having parts thereof extending through said frames clamping said panels to said frames, said panels being substantially channel shaped, said frames comprising clamps having substantially U-shaped plates engaging said channel-shaped panels.

7. A ventilation system for mines having a mine shaft including an overhead, said mine shaft being intersected by a cross shaft, said cross shaft having an overhead forming a recess in the overhead of said mine shaft, a substantially rectangular conduit received in said recess, and vertically extending stoppings in said cross shaft extending from the bottom of said cross shaft to said conduit and closing said cross shaft relative to said mine shaft at each side of said mine shaft, said conduit having a plurality of rectangular frames, pairs of horizontally extending panels, and clamp members having parts thereof extending through said frames clamping said panels to said frames, said panels being substantially channel shaped, said frames comprising clamps having substantially U-shaped plates engaging said channel-shaped panels, said clamps including threaded rods secured to said U-shaped plates and extending through said frames, and clamp elements threadedly secured on said rods engaging said frames.

8. A ventilation system for mines having a mine shaft including an overhead, said mine shaft being intersected by a cross shaft, said cross shaft having an overhead forming a recess in the overhead of said mine shaft, a substantially rectangular conduit received in said recess, and vertically extending stoppings in said cross shaft extending from the bottom of said cross shaft to said conduit and closing said cross shaft relative to said mine shaft at each side of said mine shaft, said conduit having a plurality of rectangular frames, pairs of horizontally extending panels, and clamp members having parts thereof extending through said frames clamping said panels to said frames, said panels being substantially channel shaped, said frames comprising clamps having substantially U-shaped plates engaging said channel-shaped panels, said clamps including threaded rods secured to said U-shaped plates and extending through said frames, and clamp elements threadedly secured on said rods engaging said frames, said pairs of panels being arranged to form a top, bottom,

and side walls for said conduit, said frames having top, bottom, and side frame members, and brace means terminally secured to said bottom frame member and a side frame member to rigidify said conduit.

9. In a mine ventilation overcast structure, an extensible metal duct supported in an elevated position to extend across an entry of a mine to carry a circulation of air thereacross and comprising a plurality of extensible channel-like panels supported in side-by-side relation with respect to each other in the general form of a rectangle, means detachably retaining said panels together, and support means therefor supporting the connected panels to extend across an entry in an elevated position with respect to the ground.

10. In a mine ventilation overcast structure adapted to establish a circulation of air over one entry at the intersection between two entries in a mine, an extensible metal duct comprising a plurality of channel-like panels

having parallel legs having inturned ends parallel to the webs thereof, spaced rectangular truss frame structures engageable with the inturned ends of the legs of said channels, individual clips engaging the inturned ends of the legs of said channels with said truss frame structures and detachably securing said channels thereto in side-by-side relation with respect to each other in the form of a rectangle, means supporting said duct to extend across the one entry adjacent the roof thereof, and stopping structures at adjacent ends of the cross entry comprising extensible metal stopping structures anchored to extend from one rib to the other of adjacent ends of the cross entry and to extend from the mine floor to the bottom of said duct and seal off the intersecting entry from said one entry, to establish a circulation of air through said cross entry and overcast without mixing with the circulation of air in said one entry.
